CLAIM

We claim the ornamental design for a light grid bezel, as shown and described.

DESCRIPTION

FIG. 1 is a upper right front perspective view of a light grid bezel, dashed lined portions are unclaimed;

FIG. 2 is an upper left rear perspective view of a light grid bezel, dashed lined portions are unclaimed;

FIG. 3 is a front elevational view of a light grid bezel;

FIG. 4 is right side elevational view of a light grid bezel, the left side elevational view is a mirror image thereto;

FIG. 5 is a rear elevational view of a light grid bezel, dashed lined portions are unclaimed; and,

FIG. 6 is top plan view of a light grid bezel, the bottom view is identical thereto.

The dashed lines shown in the drawings illustrating unclaimed features form no part of the claimed design.
